(57) CLAIM

The new and ornamental design for the key case, substantially as shown and described.

DESCRIPTION

FIG. 1 is a reference perspective view of a key case,

FIG. 2 is a front view of the key case,

FIG. 3 is a rear view of the key case,

FIG. 4 is a left side view of the key case,

FIG. 5 is a right side view of the key case,

FIG. 6 is a top view of the key case; and,

FIG. 7 is a bottom view of the key case.

This article is a key case in which a card-type or box-type electronic key is housed.

It being understood that the broken lines are for illustrative purposes only and form no part of the claimed design.
